CLOTHESLINE SHIELD ISSUING PULLEY

Joseph Budner, Newark, N. J., assignor of one-half to Edward E. Petti, Newark, N. J.

Application May 23, 1944, Serial No. 536,893

4 Claims. (Cl. 211—119.18)

This invention relates to improvements in clothesline pulleys including means for issuing therefrom a shield cover for the clothesline mounted thereon.

This invention has for an object to provide a clothesline pulley structure provided with a plurality of symmetrically grouped line supporting rollers mounted respectively in the radial extensions of a T-shaped yoke or frame, around and in spaced relation to a central reel upon which is wound the shield cover material to be issued therefrom for application over the outgoing course of the line; casing means being provided to enclose the shield cover material carried by said reel, said casing means being affixed to the yoke in a novel manner, whereby to be held against rotative displacement, the reel having means cooperative with the ends of said casing means to close said ends; and a transmission gearing being provided between one of said line supporting rollers and said reel, whereby to rotate the latter for automatically paying out the shield material in company with the out-going course of the line, and for automatically winding in said shield material when movement of said out-going course of the line is reversed.

The invention has for another object to provide a clothesline shield issuing pulley which is of compact and simple construction; of low production cost; and wherein the mere act of paying out or pulling in the clothes supporting course of the line automatically issues or retracts the shield cover material.

Other objects of this invention, not at this time more particularly enumerated will be understood from the following detailed description of the same.

An illustrative embodiment of this invention is shown in the accompanying drawing, in which:

Fig. 1 is a side elevational view of the novel clothesline shield issuing pulley according to the invention; Fig. 2 is a horizontal sectional view thereof, taken on line 2—2 in Fig. 1; and Fig. 3 is a central longitudinal vertical sectional view thereof, taken on line 3—3 in Fig. 2.

Similar characters of reference are employed in the above described views, to indicate corresponding parts.

Referring to the drawing, the yoke or frame of the pulley structure of this invention comprises laterally spaced T-shaped side members, each comprising oppositely extending vertical arms 11 and 12 and a rearwardly extending horizontal arm 13, all being radial to central portion 14 thereof. The extremities of corresponding ver-

tical arms 11 and vertical arms 12 are joined by transverse end members 15. The rearward end portions of the horizontal arms 13 are formed to provide in-turned end members 16 which terminate in abutting rearward extensions 17; said extensions being preferably formed to provide an attachment eye 18 to engage over a hook or the like (not shown) for the support of the pulley structure at a desired place of use.

10 Affixed to and between the central portions 14 of the yoke or frame is a transverse axle 19. Rotatable about said axle 19 is a spool or reel 20 upon which is wound a strip 21 of flexible shield material. Said shield material may comprise a textile or other suitable fabric or other comparatively thin flexible sheet material of suitable width adapted, when operatively applied to the clothesline, to fold longitudinally over said line, so as to embrace and cover the same. At one end thereof, said spool or reel 20 is provided with an annular flange 22 of suitable diameter, the periphery of which is provided with gear teeth 23. On its inner face said flange 22 is provided with a projecting boss 24 of reduced diameter. At its 15 opposite end, said spool or reel is provided with an annular flange 25 corresponding in diameter to that of the boss 24 of the gear flange 22. Said flanges 22 and 25 respectively bound the opposite sides of the body of shield strip material 21 wound upon the spool or reel.

A casing means is provided for enclosing the shield strip material 21 wound upon the spool or reel 20, the same comprising a cylindrical shell 26 made of sheet metal or other suitable material, and having an internal diameter corresponding to the diameters of said boss 24 and flange 25 of the spool or reel. One open end portion of said casing shell 26 fits and is engaged over the boss 24 of the gear flange 22, and the opposite 20 open end of said casing shell fits and engages over said spool or reel flange 25. Said latter end portion of the casing shell 26 is indented to provide notches 27 properly located to receive and straddle the arms 11, 12 and 13 of the adjacent side member of the yoke or frame of the pulley structure, thereby interlocking said casing shell with said yoke or frame against rotative movement, when the spool or reel 20 is revolved. Said casing shell is provided in its underside with an opening or slot through which the shield strip 21 may move, as it is payed off or wound onto the spool or reel 20. It will thus be obvious that said casing shell fully encloses the body of shield strip material contained on the spool or reel, thus 25 protecting the same, when not in use, from the

weather, and against soiling by dirt or other foreign matter.

Affixed to and between the outer end portions of the upwardly extending arms 11 of the yoke or frame is a transverse axle 28. Rotatable on said axle 28 is an upper line supporting roller 29, to support the normally in-going course of a clothesline 30 for free passage above the encased shield strip material spool or reel. Affixed to and between the outer end portions of the downwardly extending arms 12 of the yoke or frame is a transverse axle 31. Rotatable on said axle 31 is a lower line supporting roller 32, to support the normally out-going course of said clothesline 30 for free passage below the enclosed shield strip material spool or reel. Similarly, affixed to and between the rearwardly extending arms 13 of the yoke or frame is a transverse axle 33. Rotatable on said axle 33 is a rearward line supporting roller 34, to support the clothesline 30 for free passage around and rearwardly of the encased shield strip material spool or reel.

One of said line supporting rollers, preferably said rearward roller 34, is provided with a gear flange 35, the teeth of which mesh with the teeth 23 of the gear flange 22 of the shield strip material spool or reel, whereby rotation of said roller 34, by movement of the clothesline 30 thereover, is transmitted to and effects rotation of the shield strip material spool or reel.

In the use and operation of the clothesline shield issuing pulley, the clothesline 30 is threaded through the pulley to pass over the roller 29, thence to and over the roller 34, and thence to and over the roller 32, being thus arranged to pass freely around the encased shield strip reel which is centrally mounted in the pulley yoke or frame. The engagement of the bight of the thus arranged clothesline 30 relative to the rearward roller 34 is such that movement of the former imparts rotary movement to the roller 34 and its gear flange 35. Clothes to be suspended on the clothesline 30 are applied to the lower course of the latter, which is initially the outgoing course. As the clothesline 30 is moved in clockwise direction to issue such outgoing course, the accompanying clockwise rotation of the roller 34 and its gear flange 35 causes the latter to drive the spool or reel gear 23 in the anti-clockwise direction, thus rotating the spool or reel in anti-clockwise direction, which is the direction of rotation which automatically pays out the shield strip material 21 through the casing slot 36 onto the outgoing course of the clothesline. The user applies the thus issued shield strip material over the out-going course of the clothesline by folding the same longitudinally thereover, whereupon the clothes 37 to be suspended from the line are hung over the thus applied shield strip material 21 and fastened by clothespins 38, thus also affixing said shield strip material to the line.

It will be obvious that the applied shield strip material 21, being interposed between the clothesline and the clothes 37 hung thereon, will protect the latter from being soiled by the former.

When the out-going course of the clothesline is retracted to bring in the suspended clothes 37 for removal therefrom, the reversal of the clothesline movement will reverse the gear driven rotation of the spool or reel thus automatically winding back the shield strip material 21 upon the spool or reel and into the casing 26.

Owing to the novel form and mounting of the casing 26, the same adequately protects the shield

strip material 21 from exposure to the weather, and from dirt or other foreign matter, when not in use, thereby assuring maintenance of a clean condition thereof, and in fit condition for use from time to time.

From the above description it will be comprehended, that a very simple, compact and comparatively inexpensive automatic clothesline shield issuing pulley structure is provided by the present invention, wherein the novel form of the yoke or frame with its novel arrangement of line supporting rollers spaced around the central shield strip spool or reel, and that the novel form of the flanged spool or reel is such that the flanges thereof, while rotatable relative to the shield strip casing, nevertheless close the ends of the latter; said casing being interlocked to the yoke or frame in a novel manner so as to be held stationary relative to the rotating spool or reel.

Having now described my invention, I claim:

1. A clothesline pulley structure of the kind described comprising a frame formed by spaced T-shaped side members, a shield strip reel mounted between central portions of said frame side members, a cylindrical casing surrounding said reel, one end of said casing having means to connect the same with a frame side member, whereby to hold the casing stationary, said reel having end flange portions to rotatably fit within and close the open ends of said casing, one of said reel end flanges having peripheral gear teeth outwardly offset relative to the adjacent end of said casing, clothesline supporting rollers mounted between outer end portions of the arms of said frame side members so as to be spaced around said reel, one of said rollers having a gear means to mesh with the gear flange of said reel, and said casing having a slot through which a shield strip wound on the reel extends to a course of the clothesline.

2. A clothesline pulley structure of the kind described comprising a frame formed by spaced T-shaped side members each having oppositely extending vertical arms and rearwardly extending horizontal arms, free end portions of said horizontal arms being joined and terminating in means for suspending the pulley structure in a place of use, a shield strip reel mounted between intersecting portions of the arms of said frame side members, clothesline supporting rollers mounted between outer end portions of the arms of said side frame members so as to be spaced around said reel, intermeshing gearing between the rearward roller and said reel, one end of said casing having notched portions to straddle arms of a side frame member, whereby to interlock said casing therewith to hold the casing stationary, and said casing having a slot through which a shield strip wound on the reel extends to a course of the clothesline.

3. A clothesline pulley structure of the kind described comprising a frame formed by spaced T-shaped side members each having oppositely extending vertical arms and rearwardly extending horizontal arms, free end portions of said horizontal arms being joined and terminating in means for suspending the pulley structure in a place of use, a shield strip reel mounted between intersecting portions of the arms of said frame side members, a cylindrical casing surrounding said reel, one end of said casing having notched portions to straddle arms of a side frame member, whereby to interlock said casing therewith to hold the casing stationary, said reel having end flange portions to rotatably fit within and

close the open ends of said casing, one of said reel end flanges having peripheral gear teeth outwardly offset relative to the adjacent end of said casing, clothesline supporting rollers mounted between outer end portions of the arms of said frame side members so as to be spaced around said reel, the rearward roller having a gear means to mesh with the gear flange of said reel, and said casing having a slot through which a shield strip wound on said reel extends to a course of the clothesline.

4. A clothesline pulley structure of the kind described comprising a frame formed by spaced T-shaped side members, a shield strip reel mounted between central portions of said frame members, a cylindrical casing surrounding said reel,

one end of said casing having means to connect the same with a frame side member, whereby to hold the casing stationary, one end of said reel having an end flange provided with peripheral gear teeth outwardly offset relative to an adjacent open end of said casing which is closed by said flange, clothesline supporting rollers mounted between outer end portions of the arms of said frame side members so as to be spaced around said reel, one of said rollers having a gear means to mesh with the gear flange of said reel, and said casing having a slot through which a shield strip wound on said reel extends to a course of the clothesline.

JOSEPH BUDNER.
